INTERNAL COMBUSTION ENGINE

Carl Voorhies, Detroit, Mich., assignor to Eaton
Manufacturing Company, Cleveland, Ohio, a
corporation of Ohio

Application July 13, 1940, Serial No. 345,326

5 Claims. (Cl. 123—90)

This invention relates to internal combustion engines generally, and more particularly, concerns a novel removable guide supporting the hydraulic, self compensating tappets for operating the valves of such engines, as well as the control of fluid flow providing the operating supply of liquid medium for such tappets.

Among the objects of this invention is the improvement of the art of internal combustion engines, the provision in internal combustion engines having hydraulic self-compensating tappets for operating the valves of such engines, of novel removable tappet guide members therefor providing a directional control to the fluid flow forming the operating supply of liquid medium for such tappets; the provision in internal combustion engines having hydraulic self-compensating tappets for the valves of such engines including tappet guides, as above described, having means for causing precipitation of any foreign matter in the operating supply of the liquid medium therefor before it enters the internal mechanism of the hydraulic tappets; the provision in an internal combustion engine, as above described, of an engine block having a longitudinally bored portion providing an oil passageway intercepted by a plurality of vertically disposed borings for reception of a like number of externally grooved and shouldered annular tappet guide members removably fixed therein, and which have oil passageways therethrough extended angularly therein below and above the longitudinal oil passageway for progressive precipitation of any foreign matter in fluid flowing therethrough and bleeding fluid therefrom for the operating supply of liquid medium for the hydraulic tappets received in said tappet guide, respectively; the provision in an internal combustion engine with a hydraulic tappet guide assembly, as above described, of a plurality of tappet guides assembled in like manner in the direction of their operating fluid flow and the final tappet guide member inserted in reverse relation to the preceding members so as to provide a continuous fluid flow therebeyond metered by the body of said tappet member.

Further and other objects and advantages of the invention reside in the novel combination and arrangement of parts to be hereinafter described, in conjunction with the drawing forming a part of this specification, and pointed out with particularity in the appended claims.

In the drawing like reference characters denote corresponding parts in the several views, and in which:

Fig. 1 is a vertical sectional view through a portion of an internal combustion engine block adjacent the valve operating mechanism thereof illustrating a preferred embodiment of this invention; and

Fig. 2 is a sectional end elevation thereof.

Referring now particularly to the drawing it will be noted that there is illustrated fragmentarily an engine block 5 having a camshaft 6 provided with a plurality of cams 7 equal in number to the valves to be operated, the stems 8 of which are fragmentarily illustrated. The engine block 5 is provided with a plurality of vertically disposed borings 10, in a common plane 15 between the valve stems 8 and the underlying cams 7, and like in number thereto. These borings 10 are for reception of the tappet guide bushings, generally designated 11, and are intersected diametrically by a longitudinally extending boring 12 through the block 5 the forward end of which is arranged to be supplied with oil from the usual oil pump of the engine, not shown, and the rear end being closed by a plug 13.

The guide bushings 11 consist of annular 25 shouldered sleeve-like members arranged to seat in the borings 10 and are fixed against rotation and displacement by any suitable means, not shown. Around the outer periphery of the bushing is a grooved oil passageway 14 which provides 30 continuous communication for the longitudinal boring 12 around the guide bushings 11 which intercept the same. Oil passageways 15 and 16 extend from the outer peripheral groove 14, of the tappet guide bushings 11, in a generally inclined direction below and above the plane of the longitudinal oil passageway 12, respectively, to the hollow interior bore 17 of the guides.

Hydraulic self compensating tappet members, generally designated 20, are received in the bores 40 17 of the tappet guides, being interposed between the cams 7 and the valve stems 8. The particular tappets shown are of the mushroom type having a tappet body 21 with a shoe portion 22 thereof contacting the cam 7; although the tappets might equally as well be of the barrel type wherein the outer diameter of the tappet body is uniform throughout its length and has a hardened cam contacting lower end. The tappet constructions herein illustrated form no part of this 45 invention, being completely described, and claimed in my issued United States Letters Patent No. 2,074,034, of March 16, 1937, for Tappet construction, and for the purposes of this invention only so much detail as is necessary to the complete 50 understanding thereof will be offered, as referred

ence may be made to the aforementioned patent for a complete description of the operation thereof. The tappet body 21 has a circumferential groove or recess 25 approximately mid-way of its length and of such extent that it is always in communication with the oil supply passageway 16 during the reciprocation of the tappet 20. One or more apertures 26 extend from the groove 25 to the hollow interior or oil supply reservoir 27 of the tappet body 21.

The upper end of the hollow bore of the tappet body is shouldered and adapted to receive a hydraulic self-compensating insert unit 29 comprising a separate cylinder, a plunger reciprocable therein, and a plunger spring yieldingly maintaining the plunger off of the bottom of the separate cylinder. A one-way check valve and its surrounding cage is fitted in the bottom of the separate cylinder, and depending therefrom is a suction tube 30 which extends deep down into the oil reservoir 27 in the lower end of the tappet body 21. For purposes of this disclosure it will be understood that, with the oil reservoir 27 in the tappet body filled with oil, upon reciprocation of the camshaft 6 in its valve seating cycle, when the base circle of the cam is presented to the tappet shoe 22, the plunger spring will tend to urge the associated plunger outward of the tappet body creating a suction effect in the lower end of the separate cylinder above the check valve, and thereby unseating the same and drawing oil through the suction tube 30 from the oil reservoir 27. During the valve lifting cycle of the camshaft, by the cam 7, the oil drawn around the unseated check valve will be trapped thereabove as the check valve is forced onto its seat. It will thus be apparent this cycle is repeated as long as there is any lash in the valve gear to be taken up or compensated for, until a zero clearance is maintained therein.

The particular importance of this invention arises from the fact, that in the operation of such hydraulic self-compensating tappets the supply of fluid provided therefor is obtained from the sump or crankcase of the conventional lubricating system of the internal combustion engine, and in mechanisms of this character any foreign matter in the fluid supplied thereto is objectionable. Accordingly, the fluid supply is introduced under pressure to the longitudinal passageway 12 at the left hand side of Fig. 1, and flows in the direction of the arrows shown. This direction of fluid flow is assumed merely for purposes of illustration in conjunction with the concrete embodiment of the invention disclosed so as to picture the relative relationship of the parts. That is to say, in conjunction with the fragmentary block showing, it will be assumed the left hand tappet guide bushing of Fig. 1 is the next to the last one and the right hand tappet guide bushing 11 is the last one in the path of fluid flow along the longitudinal passageway 12. The path followed by the pressure fluid then will be through the boring 12 around the left hand tappet guide bushing 11, and back into the passageway 12 between the tappets. Some entrained foreign matter which has been carried by the pressure fluid, being heavier, will be precipitated down the inclined oil passage 15 and metered out by the tappet body 21 masking the outlet thereof into the valve chamber or back to the engine sump, as the case may be. The major portion of the fluid flow, as aforementioned, continues around the peripheral groove 14 of the guide bushing to a continuation of the passage-

way 12 between the two tappets shown. From here the pressured fluid is forced up the inclined oil channel 16 where the tappet body peripheral groove or recess 25 is in communication with the outlet therefrom during all phases of the reciprocation of the tappet, or intermittent registration as required, and from when the fluid flows into the aperture 26 to the tappet body oil reservoir 27. Incidentally the uphill climb of the oil and the reservoir also act as a settling medium for any heavy foreign particles which have not been so far precipitated from the oil line.

At the last tappet on the line of the longitudinal passageway 12, the right hand tappet of Fig. 1, it will be noted the tappet guide bushing 11 has been reversed or rotated 180° with respect to the preceding members. In this arrangement instead of the pressure fluid dead ending here and forming a potential sludge pocket there is provided a continuous fluid flow by the oil being metered past the tappet body baffling the outlet of the downwardly inclined passage 15 back to the valve chamber or oil sump. The invention is equally as well adapted for radial aircraft engines only in that instance instead of the straight longitudinal passageway 12 there would be a circumferentially extending oil channel and suitably inclined oil passages through each of the tappet guide bushings 11.

From the foregoing disclosures it will be apparent there has been described a novel tappet guide bushing and assembly for internal combustion engines providing a unique directional fluid flow for the operating supply of the hydraulic self-compensating tappets thereof, accomplishing among other things the objects and advantages of the invention first enumerated. It is to be understood, however, the specific embodiment herein illustrated is for purposes of illustration only, and all formal modifications thereof are intended to be covered within a fair interpretation of the scope and substance of the invention as defined by the following claims.

What I claim is:

1. In an internal combustion engine, the combination with a plurality of hydraulic valve tappets, of an engine block having a wall provided with a like number of cylindrical tappet guide bores having tappet guide bushings therein for receiving said tappets, said tappet guide bores and bushings having their axes extending in substantially the same direction and lying in a common plane, aligned passages extending within the wall, between consecutive bores and to the outside of the engine block and joining with circumferential passages surrounding said guide bushings, a source of liquid supply, a pump arranged between and communicating with said source of liquid supply and one end of said aligned passages for furnishing liquid thereto, and liquid passages in said guide bushings extending upwardly and downwardly from said circumferential passages for furnishing liquid to said tappets and tending to eliminate foreign matter from the aligned passages, respectively.
2. In an internal combustion engine, the combination with a plurality of hydraulic valve tappets, of an engine block having a wall provided with a like number of cylindrical tappet guide bores having tappet guide bushings therein for receiving said tappets, said tappet guide bores and bushings having their axes extending in substantially the same direction and lying in a common plane, aligned passages extending within the wall, between consecutive bores and to the

outside of the engine block and joining with circumferential passages surrounding said guide bushings, a source of liquid supply, a pump arranged between and communicating with said source of liquid supply and one end of said alined passages, liquid passages in said guide bushings extending upwardly and downwardly from said circumferential passages for furnishing liquid to said tappets and tending to eliminate foreign matter from the alined passages, respectively, and said tappet guide bushing on the other end of said alined passages being assembled in reverse relation to said other preceding bushings whereby the oil passages therein are arranged to furnish liquid upwardly to said tappet and to meter liquid downwardly around the body of said tappet, respectively, back to said source of liquid supply for continuous circulation thereof.

3. In an internal combustion engine, the combination with a plurality of hydraulic valve tappets, of an engine block having a wall provided with a like number of cylindrical tappet guide bores having tappet guide bushings therein for receiving said tappets, said tappet guide bores and bushings having their axes extending in substantially the same direction and lying in a common plane, alined passages extending within the wall, between consecutive bores and to the outside of the engine block and joining with circumferential passages surrounding said guide bushings, a source of liquid supply, a pump arranged between and communicating with said source of liquid supply and one end of said alined passages, and inclined liquid passages in said guide bushings extending upwardly and downwardly from said circumferential passages tending to eliminate entrained foreign matter from said liquid supply and to furnish liquid to said tappets, respectively, and in chronological order at each tappet.

4. In an internal combustion engine, the combination with a plurality of hydraulic valve tappets of an engine block having a wall provided with a like number of cylindrical tappet guide bores having tappet guide bushings therein for receiving said tappets, said tappet guide bores and bushings having their axes extending in substantially a radial direction and lying in a common plane, alined passages extending within the wall, between consecutive bores and to the outside of the engine block and joining with circumferential passages surrounding said guide bushings, a source of liquid supply, a pump arranged between and communicating with said source of liquid supply and one end of said alined passages, and liquid passages in said guide bushings extending upwardly and downwardly from said circumferential passages for furnishing liquid to said tappets and tending to eliminate foreign matter from the alined passages, respectively.
5. In an internal combustion engine, the combination with a plurality of hydraulic valve tappets, of an engine block provided with a like number of cylindrical tappet guide bores having their axes extending in the same general direction in a common plane and adapted to receive said tappet guides, alined passages extending between consecutive bores and joining with circumferential passages surrounding said tappet guides, and means for transmission of tappet operating-fluid extending upwardly and downwardly from said circumferential passages to the tappets, in diametrically opposite sides of the tappet guides, whereby said downwardly extending fluid transmission means is on the side presented to the direction from which the fluid flows and said upwardly extending fluid transmission means is on the side opposite thereto.

CARL VOORHIES.
